FLUID PRESSURE PUMP OR MOTOR

Robert W. Fernstrum, Detroit, Mich., assignor to
Marine Products Company, Detroit, Mich., a
corporation of Michigan

Application December 4, 1947, Serial No. 789,681

10 Claims. (Cl. 103—117)

1

This invention relates to fluid pressure pumps or motors, and, in particular, to such pumps or motors having resilient rotors.

One object of this invention is to provide a fluid pressure pump or motor having a rotor with resilient vanes which engage cam intake and outlet members arranged between cavities communicating with the intake and outlet ports respectively of the casing, these cam members being formed separately from the casing and subsequently attached thereto.

Another object is to provide a fluid pressure pump or motor with cam members of the above type having substantially flat portions extending between the cavities and also having inclined ramps at opposite ends thereof extending into the cavities so that the flexing of the vanes and the consequent acceleration and deceleration are performed within the cavities themselves and not between the cavities.

Another object is to provide a fluid pressure pump or motor with cam members of the above type having flat portions of sufficient length and with a rotor having resilient vanes spaced sufficiently close together that when one vane is leaving a flat portion, the next succeeding vane has already entered the same flat portion of the cam member, thereby providing a complete seal between the intake and outlet cavities and ports and reducing the carryover of fluid, especially at high speeds.

Another object is to provide a fluid pressure pump or motor having a rotor with resilient radial vanes on its opposite sides engaging cam members arranged between cavities communicating with the inlet and outlet ports, these cavities extending inwardly along the sides of the vanes in approximately radial directions so as to more efficiently feed the fluid to and from the rotor vanes and thereby improve performance at high speeds.

In the drawings:

Figure 1 is a vertical longitudinal section through a fluid pressure pump or motor, according to a preferred form of the invention;

Figure 2 is a top plan view, slightly reduced in size, of the left-hand end of the pump or motor shown in Figure 1;

Figure 3 is a vertical cross-section taken along the line 3—3 in Figure 2;

Figure 4 is an approximately horizontal section taken along the zigzag line 4—4 in Figure 3, with the rotor in top plan view and showing the flexing of the vane thereof against the cam plates and also the fluid supply and discharge pockets; and

Figure 5 is a fragmentary side elevation of the left half of the pump or motor casing, similar to the upper portion of Figure 3, with the rotor removed, and showing one of the cam plates and

2

the adjacent fluid supply and discharge pockets.

Referring to the drawings in detail, Figure 1 shows a longitudinal or axial section through a fluid pressure pump or motor, generally designated 10, according to a preferred form of the invention. The pump or motor 10 is provided with a casing generally designated 11, and having casing right-hand and left-hand halves 12 and 13 respectively. The casing half 12 is provided with circumferentially-spaced holes 14 and the casing half 13 with aligned threaded holes 15 for receiving machine screws 16 by which the two halves are secured together.

The casing half 12 is provided with a bore 17 and the casing half 13 with an aligned bore 18 for receiving a rotor shaft 19, the bore 18 being located within an axially projecting boss 20. The end of the bore 18 is closed by a closure plate 21 and lubricant is supplied to the left-hand end of the shaft 19 through a bore 22 which is threaded to receive the threaded stem 23 of a lubricant cup or fitting 24. While a grease cup has been shown at 24, it will be understood that any other type of conventional lubricating device may be employed, such as the well-known lubricant fittings used with a pressure lubricant gun.

In order to prevent leakage around the mid-portion of the shaft 19, the casing half 12 is provided with a counterbore 25 equipped with a packing 26 which is compressed by the tubular portion 27 of a gland 28. Extending outward in opposite directions from the portion 27 (Figure 2) are integral arms 29 which are bored as at 30 to receive bolts 31. The latter also pass through aligned bores 32 in corresponding integral arms 33 forming portions of an axially projecting boss 34 on the casing half 12 which contains the counterbore 25. By tightening the nuts 35 on the bolts 31, the tubular portion 27 of the gland 28 is forced into the counterbore 25, compressing the packing 26 to the desired extent.

The outer right-hand end portion of the rotor shaft 19 is supported by a conventional anti-friction bearing unit 36 which is mounted in a shouldered bore 37 within a bearing boss 38 and held in position by a retaining ring 39 snapped into an annular groove 40 (Figure 1). The bearing boss 38 is supported upon an arm 41 extending axially outward from the central portion of the casing half 12 and having a machined flat portion 42 at the bottom thereof to facilitate mounting the pump or motor upon an engine or other machine support. A central flange or rib 43 extends between the bosses 34 and 38 and connects them and the main portion of the casing half 12 to the arm 41, thereby strengthening the casing and increasing its rigidity. A collar 44 is secured by a set screw 45 to the shaft 19 adjacent the inner race of the anti-friction bearing unit 36 to prevent end motion of the shaft 19. A

driving pulley gear or sprocket (not shown) is mounted on the right-hand end of the shaft 19 on the opposite side of the anti-friction bearing unit 36 from the collar 44, completing the arrangement for preventing end motion of the shaft 19.

The casing half 12 is provided with a cover portion 46 (Figure 1) which has an inner surface or end wall 47 engaging the corresponding inner surface 48 of the casing half 13. The surface 48 extends around the edge of a cylindrical bore or rotor chamber 49 having an end wall 50. The lower portion of the chamber 49 is provided with a drainage port 51 which is threaded to receive a plug 52. The casing half 13 is provided with an upwardly-extending top portion 53 having intake and discharge ports 54 and 55 respectively (Figure 2). These ports are preferably threaded to receive the threaded ends of intake and discharge pipes. The ports 54 and 55 open into radially-extending pockets or cavities 56 and 57 respectively separated by a sector-shaped bridge portion 58 (Figure 5). Similarly, the cover portion 46 of the casing half 12 is provided with corresponding radially-extending pockets 59 and 60 (Figure 4) aligned respectively with the pockets or cavities 56 and 57 and similarly separated by a sector-shaped bridge portion 61.

The bridge portions 58 and 61 are bored and threaded as at 62 and 63 to receive set screws 64 by which a pair of oppositely-bent cam members 65 and 66 are secured to the bridge portions 58 and 61, the exposed surfaces 67 and 68 (Figure 4) being machined to receive the cam members 65 and 66. Each of the cam members 65 and 66 consists of a central portion 69 (Figures 4 and 5) having a flat rotor-engaging surface 70 and outwardly-inclined ramp portions 71 and 72 which have inclined contact surfaces 73 and 74 respectively. The inclined portions 71 and 72 extend outwardly into the pockets or cavities 56, 57, 59 or 60, according to where the particular cam member 65 or 66 is located.

Keyed or otherwise drivingly secured as at 75 (Figure 1), to the shaft 19 is the hub 76 of a rotor, generally designated 77. In addition to the hub 76, the rotor 77 consists of a disc 78 which is tightly secured to the hub 76 and which has molded upon and around it a vane unit 79 which is formed of elastic deformable material such as rubber or synthetic rubber. The disc 78 is provided at circumferentially-spaced intervals with holes 80 (Figure 3) through which the elastic deformable material extends so as to secure the vane unit 79 firmly to the disc 78 and hence to the hub 76.

The vane unit 79 is provided with a central rib 81 extending outward from the hub 76 and with its side walls parallel to the side walls of the disc 78. Integral with the rib 81 and positioned at intervals around it are sector-shaped blocks or projections 82 (Figure 4) of approximately the same width as the separation of the flat surfaces 70 of the cam members 65 and 66. Extending from the opposite ends of the rotor 77 and integral with the trailing edges of the blocks or projections 82 are radially extending vanes 83 which are inclined obliquely to a plane perpendicular to the axis of rotation of the rotor shaft 19, hence are inclined obliquely to the rib 81. The vanes 83 on opposite sides of the rib 81 simultaneously engage the adjacent end walls 47 or 50 of the rotor chamber 49. The vanes 83 are flexed axially almost into contact with the side walls of the rib 81 when they engage the flat contact surfaces 70 of the cam members 65 and 66.

The vanes 83 along their lower edges are cut away as at 84 from the hub portion 85 of the vane unit 79 so as to permit the vanes 83 to flex freely.

By the foregoing construction, the cam members 65 and 66 may be accurately manufactured to precise dimensions by forming them in dies in an inexpensive and rapid manner, after which they can be attached to the bridge portions 58 and 61 by the screws 64. The surfaces 67 and 68 against which they are seated are machined in the same operation with the machining of the end walls 47 and 50 of the casing halves 12 and 13. The pockets or cavities 56, 57, 59 and 60 are, of course, preferably formed during the casting operations of the casing halves 12 and 13. The rotor 77 can be rotated in either direction merely by removing it from the shaft 19 and reversing its position upon the shaft.

In the operation of the invention, the various parts of the pump or motor 10 are assembled as shown in the figures, and power is applied to the rotor shaft 19 to rotate the rotor 77. As the rotor 77 rotates in the direction of the arrow (Figure 3), it draws in fluid through the intake port 54 by way of the pockets or cavities 56 and 59, carries this fluid around the periphery of the bore or rotor chamber 49, and discharges it through the discharge port 55 by way of the pockets or cavities 57 and 60 (Figure 4). In each case, the fluid can pass freely between the pockets 56 and 59 or 57 and 60 by way of the upper outer corner portions 86 and 87 thereof (Figure 5) adjacent the ports 54 and 55, the portions 86 and 87 serving as connecting passageways between the respective cavities or pockets.

As the vanes 83 approach the bridge portions 58 and 61, they engage the ramps 71 of the cam members 65 and 66 and are flexed into the positions shown in Figure 4, closely adjacent the rib 81. As shown in Figure 4, the blocks or projections 82 are spaced at such intervals around the periphery of the rotor 77, and the flat surfaces 70 are of such comparative widths that before one pair of vanes 83 leaves the flat surfaces 70, another pair of vanes is already engaging the surfaces 70, thus giving an overlapping effect to the vanes. Thus, an effective seal is maintained and no acceleration or deceleration occurs after the vanes have left the pockets or cavities 57, 60 or entered the cavities 56 and 59. The rotor 77 is so constructed and proportioned that the vanes 83 fit snugly into the spaces 88 (Figure 4) between them and the leading edges 89 of the blocks or projections 82, thereby reducing carryover of fluid to a minimum.

While the operation of the invention has been described as that of a pump, it will be understood that it may also be used as a motor, merely by feeding pressure fluid to the port 54 and allowing it to discharge from the port 55. This will rotate the rotor 77 and rotor shaft 19, whereupon power can be taken off the latter by means of a gear, sprocket pulley or the like (not shown).

Experience with the invention has proved that the device will operate as a pump at higher pressures and at higher speeds than has been possible with pumps of this type heretofore made. Ordinarily, when a pump of this type is operated at high speed, the pump begins to be "starved" for fluid as the speed is increased beyond a particular speed, depending upon the design of the pump. The provision of the radially extending pockets 56, 57, 59 and 60, however, in the present invention, admits fluid to the vanes 83 throughout their entire lengths, down to the hub portion 85 of the

vane unit 79. The provision of the blocks 82 also fills the space more completely between successive sets of vanes 83 and decreases the fluid carry-over effect from the pockets 57 and 60 to the pockets 56 and 59 past the cam members 65 and 66.

What I claim is:

1. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam members having ramp portions inclined relatively to said end walls and extending toward said ports.

2. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam members having ramp portions inclined relatively to said end walls and extending toward said ports, said end walls having fluid intake and discharge cavities therein extending alongside said vanes and communicating respectively with said intake and discharge ports.

3. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam members having substantially flat central portions and ramp portions inclined relatively to said end walls and extending toward said ports, said end walls having fluid intake and discharge cavities therein extending alongside said vanes and communicating respectively with said intake and discharge ports.

4. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam

members having ramp portions inclined relatively to said end walls and extending toward said ports, said end walls having fluid intake and discharge cavities therein extending alongside said vanes and communicating respectively with said intake and discharge ports, said ramp portions extending into said cavities.

5. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam members having substantially flat central portions and ramp portions inclined relatively to said end walls and extending toward said ports, said end walls having fluid intake and discharge cavities therein extending alongside said vanes and communicating respectively with said intake and discharge ports, the ramp portions of the cam members on the opposite end walls of said casing being inclined in opposite directions relatively to the adjacent flat central portions of said cam members into the cavities adjoining said ramp portions.

6. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam members having ramp portions inclined relatively to said end walls and extending toward said ports, said rotor having circumferentially-spaced axially extending projections around the periphery thereof and said vanes extending laterally from said projections, said vanes on opposite sides of said rotor flexing axially toward one another into the spaces between said projections upon engagement with said cam members.

7. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam members having ramp portions inclined relatively to said end walls and extending toward said ports, said rotor having circumferentially-spaced axially extending projections around the periphery thereof and said vanes extending laterally from said projections obliquely to the axis of rotation of said rotor, said vanes on opposite sides of said rotor flexing axially toward

one another into the spaces between said projections upon engagement with said cam members.

8. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam members having ramp portions inclined relatively to said end walls and extending toward said ports, said rotor having a peripheral rib with circumferentially-spaced axially extending projections around the periphery of said rotor and said vanes extending laterally from said projections, said vanes on opposite sides of said rib flexing axially toward one another into the spaces between said projections upon engagement with said cam members.

9. A fluid pressure pump or motor comprising a casing having therein a rotor chamber with spaced end walls and spaced fluid intake and discharge ports, said end walls having bridge portions disposed between said ports, a rotor shaft rotatably mounted in said casing, a rotor mounted on said shaft and having radially extending vanes of elastic deformable material on the opposite sides of said rotor simultaneously engageable with said end walls, and cam members mounted on said bridge portions and projecting inwardly from said end walls, said vanes being disposed in flexing engagement with said cam members, said cam

members having ramp portions inclined relatively to said end walls and extending toward said ports, said rotor having circumferentially-spaced axially extending projections around the periphery thereof and said vanes being arranged in pairs of approximately V-shaped formation and extending laterally from said projections, said vanes on opposite sides of said rotor flexing axially toward one another into the spaces between said projections upon engagement with said cam members.

10. A fluid pressure pump or motor comprising a casing having therein a rotor chamber with spaced fluid intake and discharge ports and a bridge portion therebetween, a rotor shaft rotatably mounted in said casing, a rotor mounted on said shaft and having radially extending vanes of elastic deformable material on the opposite sides thereof, and a cam member mounted on said bridge portion and projecting inwardly in an axial direction, said vanes being disposed in flexing engagement with said cam member, said cam member having a substantially flat central portion and ramp portions at the opposite ends thereof inclined relatively to said flat central portion and extending toward said ports.
